UNITED STATES PATENT OFFICE.

GEORGE O. SHAKESPEARE, OF PHILADELPHIA, PENNSYLVANIA.

HOLDER FOR MEDICINAL INHALERS.

SPECIFICATION forming part of Letters Patent No. 618,211, dated January 24, 1899.

Application filed March 19, 1898. Serial No. 674,524. (No model.)

To all whom it may concern:

Be it known that I, GEORGE O. SHAKESPEARE, residing at Philadelphia, in the State of Pennsylvania, have invented certain new and useful Improvements in Holders for Medicinal Inhalers, of which the following is a specification, reference being had therein to the accompanying drawings.

This invention relates to holders for inhalers for pillows.

The object of the invention is to produce a means for attachment by which a retaining bottle or vessel for an inhaling liquid may be quickly attached to or detached from a pillow and by which it may be held to the pillow while in use.

Figure 1 is a broken plan of part of a pillow, showing the spring in the pillow and the bottle or medicine-cup and its holder in place. Fig. 2 is a perspective of the bottle or cup holder detached. Fig. 3 is a perspective of the bottle or medicine-cup detached. Fig. 4 is a broken section of the pillow with medicine-bottle and its holder applied.

A indicates a pillow for a bed or couch having a round aperture or recess in its body, as is common. To the lower part of the pillow a bottle or cup holder is secured so as to extend into the aperture. This holder is com-

posed of spring-wire bent to form inwardly and upwardly projecting wings B' B', shown as three in number; but the number of wings may be varied. Between the wings B' B' there are spaces C. The outward extensions

D of the wire are of greater diameter than the hole in the pillow and rest against the lower surface of the pillow, where they are secured by stitches or otherwise, while the wings B' B' extend toward the center of the hole in the pillow, leaving spaces C between them.

The medicine bottle or cup H has a neck H', and from the top of the neck flanges I I project radially, these flanges being of a length in the direction of the circumference of the neck to pass between the wings B' of the holder, or the flanges I be longer than the space between the wings B. The wire of which holder

B is composed may spring a little, so as to permit said flanges I to pass between the wings B' of the holder B. As will be seen in Figs. 1 and 2, the space between the wings

of the wire retainer is wider near the base of the wire than where the wings converge at their upper inner ends. This causes the flanges I to spread or deflect the wings should the flanges be wider than the narrowest part of the space. The medicine-receptacle may thus spring the wings to position to receive such receptacle in entering.

60

The cup or bottle H is preferably of glass, porcelain, or like material. In use it is filled or partially filled with the medicine which it is desirable to inhale and may contain a sponge or may have other suitable means to prevent the escape of the liquid.

To attach the cup or bottle to a pillow which has a hole therein and the holder B attached, the bottle will be passed up from below, as in Fig. 4, and the flanges I will pass through the spaces C. By turning the bottle until the flanges I lie above the wings B' the body of the bottle is brought against the lower face of the wires B', and the bottle is held within the hole or well in the pillow by the wire, the body of the bottle lying against the spring-wires. To release the bottle or cup, a rotary movement is given to the bottle or cup to bring the flanges I into register with the spaces C between the wires of the cup-holder, 80 when the bottle may be removed.

The bottle-neck should be of such length and the body of the cup or bottle, as well as the holder, should be of such form that the body H of the bottle rests closely against the arched wires. The bottle will thus be held to the pillow firmly, but can readily be detached by a partial turn and withdrawal.

The bottom of the bottle H may have a flange, as indicated in dotted lines, Fig. 4, 90 which flange may be integral with the bottle, or may be a ring or disk connected with the bottle.

This elastic wire-holder B is very cheap and when applied permanently to the vent 95 in the pillow forms a very convenient means for attaching the flanged bottle and for holding it firmly to the pillow and in a position from which it may be easily detached.

What I claim is—

1. The combination with a pillow having recess therein of a wire holder having arched wings extending into the recess in the pillow, and a medicine-receptacle having flanges

100

which may pass between said wings and turn to position to lock the receptacle to the wire fastener, all substantially as described.

2. The combination of a pillow having recess therein, of a spring-wire, looped to form catches, and a medicine-receptacle having flanges which may be passed between said catches and turned so as to be held or locked by the catches, substantially as described.

10 3. The spring-wire having arched wings with spaces between, and the medicine-cup having a neck with flanges which may pass

between the wings, by expanding the same, and having a body which fits closely against the under surface of the wings when the 15 flanges are turned above said wings, all substantially as described.

In testimony whereof I affix my signature in presence of two witnesses.

GEORGE O. SHAKESPEARE.
